SOLENOID MAGNET

Maurice S. Snell, Cranham, England, assignor to
 Dowty Equipment Limited, Cheltenham, England

Application October 16, 1951, Serial No. 251,467

10 Claims. (Cl. 317—198)

1 This invention relates to solenoid magnets of the type in which the armature is arranged coaxially with respect to the core. Hitherto it has been the practice to provide a radial air gap which surrounds the armature and separates it magnetically from the solenoid yoke. This air gap though reducing the thrust in the solenoid is nevertheless preferable to the friction that would be present if the armature were a close sliding fit within the guide bore in the yoke. The air gap has to be more than a mere working clearance because any eccentricity in the mounting of the armature would result in its tending to move into engagement with one side of the guide bore. To reduce the reluctance of such air gap, the axial dimension of the yoke where it surrounds the armature has usually been extended by flanging or flaring each side of the yoke. The term "air gap" is used herein to include an arrangement in which a non-magnetic sleeve serves to centralise the armature. Magnetically such a sleeve has no effect and is therefore the equivalent of a pure air gap.

The present invention seeks to provide an improved construction of solenoid magnet of the type referred to wherein the air gap is to all intents and purposes eliminated without the introduction of undue friction, whereby a given thrust may be obtained for less ampere turns than has been necessary with known solenoids of the type referred to, or whereby a similar sized solenoid will afford greater thrust.

The invention is illustrated by way of example in the accompanying drawings, of which:

Figure 1 is a central sectional view of one form of solenoid magnet;

Figure 2 is a central sectional view of another form of solenoid magnet; and

Figure 3 is a central sectional view of a further form of solenoid magnet.

The solenoid magnet in Figure 1 comprises a yoke having a disc-shaped base 3, a core 4 and a housing 5 secured to the base 3 by swaging, while a field winding 6 is disposed in the annular gap between the core 4 and the housing 5. The construction illustrated is more specifically intended for operation of a hydraulic valve and to this end a pair of fixing bolts 7 and 8 are let into the base 3 for securing the latter to the body of a valve.

The armature 9 consists of a disc having one face extended to form a narrow flange 11 and the other face extended to form a substantially wider radial flange 12. The space between the flanges 11 and 12 thus forms a circular recess within which the inner edges of a plurality of sector-

2 shaped links 13 are received, these links 13 in effect forming part of the armature. The outer edges of the links 13 fit in a recess 14 in the housing 5, the links 13 being arranged to fit the recess 14 and the recess in the armature 9 so that they can turn freely through a small angle on either side of a transverse plane. It is preferable to have a fairly large number of links 13, for example twelve or more, so that their outer and inner curved edges will not bind in the respective recesses when they are turned out of the transverse plane. The radial edges of the sector-shaped links 13 are in sufficiently close proximity with each other to provide a substantially unbroken flux path between the housing 5 and the armature 9.

The upper end of the housing 5, being reduced in thickness by the formation of the recess 14, is turned outwardly to form a narrow flange 15 on to which the wider edge of a truncated conical sheet metal cover 16 is secured by rolling or pressing. This cover 16 serves to locate a ring 28 of flexible rubber or the like which retains the outer curved edges of the links 13 in the recess 14, and also to locate a coil spring 17 which presses on the inner portions of the links 13 to prevent them from vibrating between the flanges 11 and 12 of the armature 9.

The armature 9 is riveted to a screw-threaded bush 18 on which an adjuster head 19 is fitted, while a coil spring 21 is interposed between the head 19 and a flanged collar 22 which rests on a pin 23 slidable in the bush 18. This pin 23, which is of non-ferrous metal, is slidably and centrally mounted in the core 4 and thus serves to guide the movement of the armature 9 towards and away from the core 4.

When the field coil 6 is energised, the armature 9 is attracted towards the core 4 by a force which is greater on account of the floating contact provided between the armature 9 and the yoke (the housing 5) by the links 13, than would be the case using a conventional armature with an air gap separating it from the yoke. The return force on the armature is provided externally by a spring-loaded spindle 24 which is associated with the valve, not shown, and upon which the pin 23 acts. The attractive force on the armature 9 is applied resiliently to the pin 23 by means of the spring 21, and by this means the full force of the solenoid magnet can be utilized in initiating opening of the valve, while the energy built up in the spring 21 is sufficient to complete the opening of the valve.

The pre-loading of the spring 21 can be ad-

justed by turning the head 19 on the bush 18 into the required position, in which it is held by the engagement of a spring tag 25 in one of a number of serrations 26 formed on the head 19. A flexible rubber cap 27 is fitted over the housing 5 and the armature may be moved by hand if desired by pressing through this cap 27 on the head 19.

Figure 2 shows in simple form, a cylindrical armature 31 movable axially within the field coil 32 against a shortened core 33 which is attached to the yoke 34. The armature 31 has a circular recess 35, and the yoke 34 a circular recess 36, which receive the inner and outer curved edges respectively of a plurality of links 37. These links 37 are similar in shape to those in the preceding example but are greater in radial length in proportion to the size of the yoke, and they also in effect form a part of the armature since they are movable.

The armature 31 has above the recess 35 a wide radial flange 38 to increase the flux between the armature and the links 37. A pin 39 of non-ferrous material fixed in the armature 31, serves to guide the latter in the yoke 34 and in a cap 40 fitted to the yoke.

In Figure 3, a further alternative construction is shown wherein a number of link-like sectors 41 extend radially inwards from a circular recess 42 in the yoke 43, to a recessed collar 44 of non-ferrous material which is fixed on, or integral with a pin 45 mounted slidably in the core 46. The inner portion of the links 41 overlap the face of the core 46 and are preferably arranged to enter into surface contact with it when the solenoid magnet is energised.

It will be realized that the armature 31 in Figure 2 and the collar 44 can if desired be mounted resiliently with respect to their respective pin 39 and 45, in a manner similar to the resilient coupling shown between the armature 9 and pin 23 in Figure 1.

While the solenoid magnets in the preceding examples have been described as suitable for the operation of hydraulic valves, they are in fact suitable in general application where a powerful movement over a relatively short stroke is required.

I claim:

1. A solenoid magnet comprising a spool winding, a core of magnetic material axially disposed within said winding, a yoke also of magnetic material mounting one end of said core and directed lengthwise of said winding, externally thereof, to a termination adjacent the opposite end of the winding, a centrally disposed member located at said opposite end of the winding, an armature including a plurality of oppositely disposed link-like elements each of magnetic material directed radially outwardly from said centrally disposed member to said yoke, pivotal mounting means formed upon the yoke and upon the centrally disposed member, respectively, and engaged with the outer and inner ends of said link-like armature elements for tilting of the latter, and constituting a magnetically conductive path from the yoke to and along said elements, and guide means wherewith said centrally disposed member is operatively engaged, to constrain said member to movement only axially of the winding, towards and from the core.

2. A solenoid magnet comprising a spool winding, a core of magnetic material axially disposed within said winding, a yoke also of magnetic material mounting one end of said core and directed lengthwise of said winding, externally thereof, to

5 a termination adjacent the opposite end of the winding, an armature of magnetic material centrally disposed adjacent that end of the core which is opposite its yoke-mounted end, means guiding the armature for movement axially of and towards and from the core, a plurality of link-like elements of magnetic material directed radially from the armature to the yoke, and means forming a pivotal mount upon the yoke for the outer ends of said link-like elements, and upon the armature for their inner ends.

3. A solenoid magnet as in claim 1, in which said central member is of magnetic material and constitutes the principal component of the armature.

4. A solenoid magnet as in claim 1, wherein the yoke surrounds the winding and the link-like elements radiate in all directions from the centrally disposed member to the yoke.

20 5. A solenoid magnet as in claim 3, wherein said central member is formed with a radial flange which overlaps a substantial portion of each link-like part and is adapted thereby to increase the magnetic flux between said centrally disposed member and said link-like parts.

6. A solenoid magnet as in claim 5, wherein said centrally disposed member comprises a disc from which said radial flange projects in substantial contiguity with one face of said disc.

7. A solenoid magnet as in claim 2, wherein the yoke is formed as a generally cylindrical housing surrounding the winding, and the link-like elements radiate in all directions from the armature to the yoke, and are complementally sector-shaped, with their radial edges adjoining.

30 8. A solenoid magnet as in claim 7, including resilient means arranged to press axially upon the several link-like elements, to minimize vibration of the latter relative to said yoke and said armature.

9. A solenoid magnet as in claim 2, including a pin guided in the core for axial movement, and projecting through the armature to constitute the guiding means for the latter's axial movement, but itself movable axially relative to the armature, and spring means interposed between said armature and said pin.

10. A solenoid magnet comprising an open-ended cylindrical yoke of magnetic material circumferentially grooved interiorly about its open end, a field winding, disposed axially within said yoke, a core disposed within the axis of said winding, a circumferentially grooved central member located axially adjacent the end of said winding, at the open end of the yoke, a plurality of complementally sector-shaped elements collectively constituting a centrally apertured armature disk, formed of magnetic material and seated at their axially inner ends within the groove of said central member, and at their outer circumferential ends within the yoke's groove, to overlie the open end of the yoke and winding, and means guiding said central member for movement axially of the core, for approach or recession of said central member and armature elements by hinging movement of each of the latter in the respective grooves.
